PUMPING HEAD AND OPERATING
MECHANISM FOR WELLS

Joseph F. Joy, Pittsburgh, Pa., assignor to Joy
Manufacturing Company, Pittsburgh, Pa., a
corporation of Pennsylvania

Application February 28, 1950, Serial No. 146,882

10 Claims. (Cl. 60—51)

1 This invention relates to a pump, and more especially to a pumping head and operating mechanism of the type used on oil wells.

Modern oil wells often penetrate to very great depths, sometimes as far as ten or fifteen thousand feet. Pumping oil or other liquid from such great depths necessarily takes an enormous amount of power. Inasmuch as the sucker rod drops due to its own weight, power need be applied only to raise it. In order to avoid the large capacity power sources which would be required if the power were applied only half of the time (i. e., to raise the sucker rod), efforts have been made to balance the system. These efforts have not been wholly successful in producing the results desired, and a much improved balanced system is needed.

It is, accordingly, an object of this invention to provide an improved pumping head and operating mechanism for wells in which the pump drive delivers power continuously through a distribution and control means which provides power to lift the sucker rod when necessary and stores power while the rod is being lowered. This and other objects are accomplished in a pump drive having a power distributing and control means consisting of an automatic control valve connected to the power utilizer (the pump head) and to an accumulator. Hydraulic power is supplied constantly to the control valve, which alternately provides power to the pump head cylinder and to the accumulator. When not receiving fluid under pressure from the hydraulic fluid pump, the cylinder and accumulator are connected to discharge fluid under pressure to the pump, thus serving in effect to supercharge the pump. In the preferred embodiment of the invention, a second accumulator is connected to the pump head cylinder and a safety cutoff valve is positioned in the conduits between the hydraulic fluid pump and the control valve.

In the drawings:

Fig. 1 is a side elevation view of a pump head embodying the invention.

Fig. 2 is a detailed longitudinal section, on a larger scale, through the pump head.

Fig. 3 is a view in section on the same scale as Fig. 2, but showing the lower end of the connecting rod and the lower end of the pilot valve rod.

Fig. 4 is a longitudinal sectional view on line 4—4 of Fig. 1, showing on an enlarged scale the details of the automatic control valve.

Fig. 5 is a view with parts broken away and in

section of the automatic cutoff valve and its connection in the hydraulic system.

Fig. 6 is another sectional view of the cutoff valve, but showing it in its operating position in which communication is cut off between the hydraulic pump and the control valve, and the pressure fluid from the pump is merely by-passed from the pump discharge to the pump intake through the valve.

Fig. 7 is a side elevation view, with parts broken away and in section, of the cutoff valve shown in Fig. 5, and shows a signal switch attached to the cutoff valve.

Fig. 8 is a schematic diagram of the hydraulic and electric circuits of the invention.

Fig. 9 is a view in section substantially on line 9—9 of Fig. 1, but on a substantially reduced scale.

Fig. 10 is a diagrammatic view of the control valve showing it in position to direct hydraulic fluid under pressure from the hydraulic pump to the pump head, and to conduct hydraulic fluid from the accumulator to the hydraulic pump.

Fig. 11 is a diagrammatic view showing the control valve in a position in which the pilot valve has been moved from the position shown in Fig. 10 to a position in which hydraulic fluid under pressure is admitted to the upper end of the valve for the purpose of moving the control valve to the position shown in Fig. 12.

Fig. 12 is a diagrammatic view of the control valve showing the valve in position to direct fluid from the hydraulic pump to the accumulator and to receive fluid from the pump head to the hydraulic pump; and

Fig. 13 is a diagrammatic view showing the pilot valve moved from its position of Fig. 12 into position to admit fluid under pressure to the lower end of the valve in order to move the valve to the operating position shown in Fig. 10.

Figs. 1 and 2 show an oil well pump head having a hydraulic lift cylinder 2 in which a piston 4 is mounted for reciprocation. Piston 4 is secured to a piston rod 6. Piston rod 6 is connected at its lower end by any suitable means as by a polished rod grip 8 and polished rod 9 to the sucker rod 10 and carries a pilot valve actuator 12.

Lift cylinder 2 of the oil well pump head is preferably a single acting hydraulic cylinder having a fluid connection 14 at its lower end to supply hydraulic fluid under pressure, and having restricted communication with the atmosphere at its upper end by means of one or more ports 16. A protective cap 18 is preferably pro-

vided to keep dirt out of the ports 16. An accumulator 20 of the enclosed bladder type, such as is shown in U. S. Patent No. 2,256,835 to Mercier, is preferably mounted to communicate with the lower end of cylinder 2 by way of a one-way restriction connection 21 in order to provide capacity to receive the discharge of hydraulic fluid from the cylinder 2 and the hydraulic pump after the control valve reverses near the end of the downward stroke of piston 4. The considerable kinetic energy of the pumping mechanism, in motion during the downward stroke, must be absorbed by some means. Such means are provided by the accumulator 20.

The connection 14 preferably consists of a conduit connected at its one end to the lower end of the aforesaid cylinder 2, and at its other end to an automatic control valve 22. Connection 14 is preferably provided with a charge connection 23 (Fig. 8), to permit a fluid charging unit to be connected for the purpose of charging the system with hydraulic fluid in the desired amount and to the desired pressure. A purge tank 24 is preferably provided in the conduit 14 in order to allow the purging or escape of entrained air by way of a manually operable valve 26.

The automatic control valve 22 is provided with a pilot valve which will be described in greater detail below. The pilot valve is reciprocated by means of actuating rods 27 at its upper end and 28 at its lower end. Rods 27 and 28 carry collars 29 and 30 respectively, to be engaged by pivotally mounted arms 31 and 32 respectively. The arms 31 and 32 are pivotally mounted to project through slots in a substantially cylindrical casing 33. In the preferred form of the invention, the casing 33 is provided with a plurality of slots 34 and 35. A bracket 36 is preferably mounted adjacent the slots 34, and a bracket 37 adjacent the slots 35. The brackets have openings 38 to receive the hinge pins 39 of the pivoted arms 31 and 32. As will be understood by those skilled in the art, the slots 34 and 35 admit of a certain amount of choice in the location of arms 31 and 32 to permit variation in the length of operating stroke of the pump which is actuated by rod 6.

As is best seen in Figs. 2 and 3, arm 31 carries an extension 40, with a roller 42 at the end of the extension and another roller 44 at the angle formed by the extension 40 with its arm. Similarly, arm 32 carries an extension 45, with a roller 48 at the end of the extension and another roller 50 at the angle formed by the extension 46 with its arm 32. The actuator 12, the arms 31, 32, their extensions, and the rollers, are so proportioned as to permit a considerable amount of overtravel by the piston 4 and actuator 12 after reversal of the pilot valve. Moreover, the angle formed by the extensions with their respective arms is such as to hold the end rollers 42 and 48 in the path of the actuator 12 when the latter moves toward a roller to reverse the position of the pilot valve.

As is best seen in Fig. 3, polished rods 8 are connected by means of a boss 51 to the lower end of actuator 12. The boss 51 and arm 32 with its associated extension and rollers are so proportioned that arm 32 is not engaged by the boss 51, but holds its extreme counterclockwise position until tripped by the actuator 12.

In order to hold actuator 12 against excessive lateral movement, guides 52 (one of which is shown in Fig. 3) may be provided at opposite

sides of actuator 12 to engage in slots or, preferably, enclosed guideways 53 in the casing 33.

A second accumulator 54, of the enclosed bladder type referred to above, is connected to the control valve 22 by means of a conduit 56. Hydraulic fluid under pressure is supplied to the control valve 22 by means which include a conduit 58 and a conduit 60, and fluid is returned from the valve to the hydraulic fluid pump by means which include a conduit 62 and a conduit 64. The fluid pump referred to is shown at 66 in Figs. 5 and 8, and, in order to permit variation of the output of the well, is preferably a manually controllable, variable displacement pump. Pump 66 is provided with discharge and intake connections 66a and 66b respectively.

The means to conduct fluid under pressure from the fluid pump 66 to the control valve 22, and the means to conduct fluid from the valve 22 to the pump 66, also includes the body 68 of a cutoff valve indicated generally at 70. The housing or body 68 is provided with a central bore having a relatively large diameter at its lower end, hereinafter referred to as bore 72, and a smaller diameter at its upper end, hereinafter referred to as bore 74. As is readily seen in Fig. 5, portions of both bores are included in the means to conduct fluid under pressure from the fluid pump 66 to the control valve 22, and a portion of bore 72 is included in the means to conduct fluid from the valve 22 to the pump 66. To that end, conduit 58 communicates with the central bore of the valve body by means of a threaded bore 76 intersecting the bore 74 of the valve body; conduit 60 communicates with the central bore by means of a threaded bore 78 which intersects bore 72; conduit 62 communicates with the central bore by means of a threaded bore 80 which intersects bore 72; and conduit 64 communicates with the central bore by means of a threaded bore 82, which also intersects bore 72.

Reference will now be had to Fig. 4 for a detailed consideration of the automatic control valve 22. A valve body or housing 86 is provided with a central bore in which is fitted a sleeve 88. The housing 86 is provided with annular grooves 90, 92, 94, 96, and 98. Sleeve 88 is provided with five sets of ports 100, 102, 104, 106, and 108 aligned with annular grooves 90, 92, 94, 96, and 98 respectively.

A valve member indicated generally at 110 is provided with end pistons 112 and 114, and with lands or plugs 116 and 118 between the pistons 112 and 114. The smaller diameter of the valve member 110 between the pistons and the lands forms, with the pistons and the lands, a plurality of grooves 120, 122 and 124. As will be understood by those skilled in the art, the pistons 112 and 114 and the lands 116 and 118 preferably provide a smooth sliding fit.

The valve member 110 is provided with a central bore 126 between the pistons 112 and 114. The pistons are hollow, providing larger bores than the bore 126 in communication with that bore. A set of ports 128 is arranged in the valve member between piston 112 and land 116; a second set of ports 130 is provided in the valve member 110 between the lands 116 and 118; and a third set of ports 132 is provided between the land 118 and the piston 114. The lands 116 and 118 are so spaced as to completely plug or cover the ports 102 and 106 respectively, with the valve member 110 located midway between its two extremes of movement, as seen in Fig. 4.

A pilot valve indicated generally at 134 is carried on the actuating rods 27 and 28 and is mounted for movement in the bore 126. Pilot valve 134 is provided with a central bore which is blocked off or plugged by a plug 136 substantially midway between its ends, thus dividing the central bore into two parts 137 and 138. The pilot valve carries end lands 140 and 142 which fit in the central bore 126 of the valve member 110. As can be seen in Fig. 4, land 140 is disposed in that end of bore 126 which is associated with piston 112, and land 142 is disposed in that end of bore 126 which is associated with piston 114. Actuating rod 27 is secured to the pilot valve by means of a head 144, which is provided with radial ports 146 to communicate the bore half 137 with the hollow of piston 112 and thereby the interior of sleeve 88. Actuating rod 28 is connected to the pilot valve by means of a head 148 which is provided with radial ports 150 to communicate the bore half 138 with the hollow of piston 114 and thereby the interior of sleeve 88.

Pilot valve 134 is provided midway between its ends with a land 152. A land 154 is provided between the lands 140 and 152. A land 156 is provided between the lands 142 and 152. The lands 140, 142, 152, 154 and 156 are of such a diameter as to provide a smooth sliding fit of the pilot valve 134 in the bore 126. Under some circumstances, it may be found desirable to make one or more of the lands small enough to provide a little clearance between the outer periphery of the land and the bore 126, as is shown in Fig. 10 of my copending application Ser. No. 73,625, filed January 29, 1949.

Pilot valve 134 is of a smaller diameter between the lands to provide a groove 158 between lands 140 and 154; a groove 160 between the lands 154 and 152; a groove 162 between the lands 152 and 156; and a groove 164 between the lands 156 and 142. A set of ports 166 communicates the bore 137 with the groove 160, and another set of ports 168 communicates the bore 138 with the groove 162.

The valve is provided with suitable end caps 170 which will not be described in detail herein, inasmuch as the details thereof form no part of this invention and are, furthermore, set forth in my above-identified patent application.

Reference is now made to Figs. 5, 6 and 7 for a detailed consideration of the cutoff valve 70. It was pointed out above that conduits 58 and 60 communicate through the bore 74 and the upper end of bore 72, and that conduits 62 and 64 communicate through the lower end of bore 72. A spool-type valve member 172 is mounted for reciprocation in the two bores 72 and 74. Valve member 172 consists of a large diameter piston 174 reciprocable in the bore 72 and a smaller piston 176 reciprocable in the smaller bore 74. In its operating position in which fluid is allowed to pass from pump 66 to the valve 22 by way of valve 70, piston 174 occupies a position in the bore 72 between the two connections 78 and 82, as is seen in Fig. 5. With the valve in this operating position, piston 176 is at the upper end of bore 74. Piston 176 is provided with bleed passages 177 to prevent the pocketing of fluid in the hollow of valve member 172 and below piston 174 when member 172 is moved downward into cutoff position.

At its upper end, valve member 172 is provided with an extension in the form of a rod 178. Rod 178 carries near its upper end a pair of ears 180

and 182. Outward and upward extending arms 184 and 186 are mounted on the upper end of the valve body 68, preferably integral therewith. Arms 184 and 186 carry mounting ears 188 and 190 which cooperate with the ears 180 and 182 respectively, to mount a pair of springs 192 and 194 respectively.

The two mounting units are identical, so it will suffice to describe one of them in detail. The ear 182 pivotally carries a plunger 196, which cooperates with a socket 198, which is in turn pivotally carried on the ear 190. The spring 194 is compressed between spring pads 200 and 202 on the plunger and socket respectively. Thus, the rod 178, arms 184 and 186, springs 192 and 194, and their associated mounting means form a toggle mechanism having a spring bias which opposes the downward movement of the valve member 172.

It will be noted that the pistons 174 and 176 differ in diameter by only a very small amount, with the result that the annular areas of these pistons which are exposed to the pressure in bore 74 are not greatly different. This small difference in areas makes it possible to use relatively light or "soft" springs 192 and 194 to oppose downward movement of valve member 172 from the operating position shown in Fig. 5 to the operating position shown in Fig. 6.

Referring now to Fig. 7, it will be seen that rod 178 also carries at its upper end, on the link to which ears 180 and 182 are attached, a substantially horizontally extending arm 204. The outer end of arm 204 carries an adjustable, downward extending abutment 206 in the form of a set screw. Valve body 68 carries a switch 208 having an actuating plunger 210 positioned and aligned to be engaged by the abutment 206. The switch 208 is disposed in the circuit of any suitable signal device, such as a light or a bell 212, by means of electrical conduit 214. The circuit includes any suitable power source 216.

As will be understood by those skilled in the art, the signal means may if desired comprise mechanism for shutting down the fluid pump drive. To that end, the switch 208 could be used to operate a relay to interrupt the power supply to the hydraulic pump drive motor, such as shown at 218, where the latter is electrically driven. Inasmuch as many oil field operations are performed with small internal combustion engines, the switch 208 could be disposed in the ignition circuit of such engine, to the end that opening of switch 208 would open the ignition circuit and stop the engine. In that case, of course, switch 208 would be a normally-closed switch instead of the normally-open switch shown in Fig. 8.

Reference is now made especially to Figs. 1 and 9, showing the improved base of the oil well pump head. As can be seen in these two figures, the pump head is supported on an open ring 220 and legs 222, the assembly forming a tripod type of support for the pump head. The ring is secured in place by being fastened as by means of bolts 223, 224, and 225 to a base plate 226 mounted on any suitable ground support members 227. A fourth ground support member 228 is provided for engagement by the ring 220 when it is swung out of pumping position into the dotted line position shown in Fig. 9 to provide better access to the well. To enable the easy swinging of the pump head about the bolt 223 as a pivot, a handle 230 is provided. Handle 230 is removably engageable in a socket 232 suitably

secured to the ring 220. The ground support member 226 is provided with an opening 234 to receive the bolt 224 to hold the ring 220 in the position shown in dotted lines in Fig. 9.

Operation

Before describing the operation of the pumping head as such, the steps required to prepare the system for such operation will be set forth here. To prepare the system for operation, it is preferable to start by "weighing the well." By reason of the weight of the sucker rods, those rods will normally be at the bottom of their stroke; what is meant by "weighing the well" is determining the approximate weight of the rods, or the force required to balance the reciprocating parts of the entire pump.

This is accomplished by filling the system with oil (or other suitable liquid) under pressure until the sucker rods and other reciprocating parts are caused to move upward. As will be understood by those skilled in the art, the charging apparatus will be connected to the connection 23 (Figs. 1 and 3), and the charging apparatus will normally be provided with a gage to indicate pressure. The gage pressure in pounds per square inch on the oil, when upward movement takes place, should be noted as "weight of well"; that is the pressure required to balance the moving parts. When this pressure is known, the air end of the accumulators 23 and 54 should be charged with air or other gas to pressure slightly in excess of the pressure indicated by the gage indicating the weight of the well. Oil is then added in such amount as will move the rods upward to approximately the center of the working stroke, whereupon the working or moving parts may be considered as being "in balance" and ready for trial operation.

By trial operation is meant that period during which entrapped air is purged from the oil in the system by way of purge tank 24 and valve 26, and make-up oil is introduced; during this stage, gas is added to or bled from the accumulators to obtain the proper balance of the working parts and to achieve smoother operation. When the system is properly balanced, a pressure gage in the discharge line of the hydraulic fluid pump should indicate approximately the same pressure on the down-stroke as it shows on the up-stroke of the sucker rod.

Reference is now made to Fig. 8, in particular, for a detailed discussion of the normal operation of a pump head made according to this invention. The normal operating position of cutoff valve 70 is that shown in Fig. 5, in which position the hydraulic fluid pump 66 delivers fluid under pressure to the automatic control valve 22 by means consisting of conduit 69, a part of the central bore of valve 70 including portions of bores 72 and 74, and conduit 53. Let it be assumed that valve 22 is in the operating position shown in Fig. 10. Valve 22 always receives fluid under pressure by way of conduit 58. With valve 22 in the position shown in Fig. 10, and as shown in the dotted line in that figure, fluid flows under pressure from conduit 58 into the annular groove 94, through ports 104, into groove 122, through ports 102, into groove 92, to the pump head cylinder 2 by way of conduit 14. Fluid under pressure is thereby admitted to the under side or face of piston 4, and raises it to lift piston rod 6 and the connected sucker rod 10.

Meanwhile, accumulator 54, which has been charged with fluid under pressure during the previous downward stroke of piston 4, discharges

its fluid under pressure by way of conduit 56 into annular groove 96 of valve 22, through ports 108 into groove 124, out through ports 108, into groove 98 as shown by the dot-dash line in Fig. 10, and back to the fluid pump 66 by way of conduit 62, a part of the central bore of valve 10 including a portion of bore 72, and conduit 64. Thus, the fluid under pressure from accumulator 54 supercharges fluid pump 66 by providing hydraulic fluid under pressure to the pump intake.

A piston 4 nears the upper limit of its movement, the actuator 12 (Fig. 3) engages the pivoted arm 31 (Fig. 2) and moves it counter-clockwise about its pivot 39. This counter-clockwise movement causes arm 31 to engage collar 29 on actuator rod 27 and moves the rod downward, moving the pilot valve 134 from the position it occupies in Fig. 10 to the position shown in Fig. 11. In the latter position, fluid under pressure is delivered from pump 66 to conduit 58, into groove 94, through ports 104 into groove 122, through ports 106 into annular groove 96 and out through conduit 56 to the accumulator 54. Thus, during the return or downward stroke of piston 4, accumulator 54 is connected with fluid pump 66 and is charged with hydraulic fluid under pressure.

With the parts of valve 22 in the operating position shown in Fig. 12, fluid under pressure is admitted from conduit 58 into the annular groove 94, through the ports 104, into the groove 122, out through ports 106, into annular groove 96 and out through conduit 56 to the accumulator 54. Thus, during the return or downward stroke of piston 4, accumulator 54 is connected with fluid pump 66 and is charged with hydraulic fluid under pressure.

Meanwhile, because of the downward movement of piston 4, occasioned by the tremendous weight of the sucker rods, piston 4 moves downward and forces hydraulic fluid out of cylinder 2 by way of conduit 14 to valve 22, where the fluid enters groove 92, passes through ports 102 into groove 120, out through ports 100, and to the pump intake by way of conduits 62 and 64, and a portion of bore 72 of valve 10. Thus the pump is also supercharged during this phase of the cycle of operation.

As the piston 4 nears the lower end of its stroke, the actuator 12 engages the arm 32 (Fig. 3) and moves it clockwise about its pivot 39. This movement causes the outer end of arm 32 to engage collar 39 and moves actuator rod 28 upward, moving the pilot valve from the position it occupies in Fig. 12 to the position shown in Fig. 13. In the latter operating position, fluid is admitted under pressure from conduit 58 into groove 94, whence it passes through ports 104 into groove 122, into ports 108, into groove 102, through ports 108, through the bore 138, and outward through the radial ports 150. Here fluid is admitted under pressure to the entire lower end of piston 114 and head 148, moving the valve into the operating position shown in Fig. 10, whereupon the cycle begins all over.

By reference to my above-identified patent application, it will be well understood by those skilled in the art that fluid pressure will normally move the valve member 110 and the pilot valve 134 from the position shown in Fig. 11 to the position shown in Fig. 12. However, if the main valve member 110 should stick for some reason or other, the mechanical actuation of the pilot valve 134 will loosen the main valve member 110, be-

cause of the abutment of the inner face of the head against the end of the inside of the piston in which the head is located.

It will further be understood by reference to the above-identified patent application that the pilot valve will normally reach the end of its movement first, and that the clearance provided between the outer periphery of the end land on the pilot valve and the bore 126 of the main valve will provide a metering effect of the fluid which is being expelled from that end of the valve to which the main valve member and the pilot valve are moving. This metering effect will serve to cushion the stop of the main valve member 110.

Reference will now be made in detail to the operation of the cut-off valve 70. Let it be assumed to begin with that the sucker rod breaks as the piston 4 moves downward. If failure occurs during this part of the cycle, it is evident that the pressure in the bore 72 below piston 174 will drop to substantially nothing, because during this part of the cycle the cylinder 2 is discharging fluid to the pump intake. When a sucker rod breaks, the weight on the piston rod 6 will be substantially reduced, thus diminishing the pressure under which cylinder 2 discharges its fluid through the valve 22, through conduit 62, bore 72 and conduit 64. The pressure, nevertheless, in bore 74 above piston 174 will still be very high, because the pump is discharging through bore 74 into the accumulator 54. There will thus be a substantial pressure differential exerting a downward force on the piston 174 sufficient to overcome the bias of springs 192 and 194, moving the spring-toggle-operated mechanism past its dead center, and into the position shown in Fig. 6.

With the parts as shown in Fig. 6, piston 174 completely cuts off communication between conduits 62 and 64, and piston 176 completely cuts off communication between conduits 58 and 60. However, with the parts in this position, flow is readily permitted between conduits 60 and 64. Thus, the automatic control valve is by-passed by the new operating position of the cutoff valve 70.

When the toggle mechanism moves into the position shown in Fig. 6, the abutment 206 engages the plunger 210, and closes the circuit for the signaling device 212. The signaling device is located where the signal will be brought to the attention of the operator who will be apprised of the fact that something is wrong and will then shut down the machine and take steps to correct the difficulty.

Alternatively, a normally-closed switch instead of the normally-open switch shown at 208, interposed in the ignition circuit of an internal combustion engine or in the relay circuit of an electric drive motor, would shut down the drive means and thus stop the fluid pump. Other variations on the control means will occur to those skilled in the art.

Let it now be assumed that the sucker rod breaks on the upstroke of piston 4. During this phase of the cycle, cylinder 2 is connected to receive fluid under pressure. Therefore, when the break occurs in this phase of the cycle, the pressure in the conduits 58 and 60 and, therefore, the pressure above piston 174, will fall to substantially zero. The pressure below piston 174 will continue high, because during this phase of the cycle the accumulator 54 is discharging oil under pressure to the pump intake. Valve member 172 will, therefore, remain in the posi-

tion shown in Fig. 5 until piston 4 has moved to its upper limit of movement, whereupon actuator 12 will reverse the pilot valve 134. With the valve reversed, the accumulator is again connected to receive fluid under pressure from the pump, whereupon the conduits 58 and 60, and the upper face of piston 174 are subjected to pressure. The valve is then operating under the same circumstances as when the sucker rod breaks on the downward stroke. That operation was described above and need not be repeated here.

It may be noted that, if a sucker rod should break on the up-stroke, piston 4 nevertheless does not move upward fast enough to damage the upper end of cylinder 2, for the reason that oil cannot be supplied fast enough to cylinder 2. The capacity of pump 66 is such that, even in the absence of a back pressure on the discharge, it will not discharge oil in sufficient volume to move piston 4 at an injurious speed. Moreover, accumulator 20 discharges oil through the connection 21, which is designed to limit the discharge of oil to a safe rate. Accordingly, although the rate of discharge of oil from pump 66 and accumulator 20 into cylinder 2 will under these circumstances be greater than under normal operating conditions, it will still not be so great as to move piston 4 upward fast enough to damage the pump cylinder. It will of course be understood by those skilled in the art that the connection 21 restricts oil flow in only one direction, and that oil may be forced into accumulator 20 without hindrance on the part of connection 21.

Reference will now be had to Fig. 9 for an understanding of the operation of the swingable base of my improved pumping head. With the pump head disconnected, bolts 224 and 225 are removed. Handle 230 is inserted in socket 232, and the pump head is swung about bolt 223 into the dotted line position shown in Fig. 9. Bolt 224 is then screwed into threaded opening 234 to hold the pumping head in place. After work on the well has been completed, the pumping head is restored to its normal operating position.

It will be evident to those skilled in the art that the oil well pumping head set forth herein provides a nicely balanced system in which the fluid pump works full time instead of a hydraulic pump twice as large working half of the time. Furthermore, an improved pumping head made according to this invention is readily swung out of the way to permit work on the well to take place, and is as readily swung back into place following the completion of such work. Other advantages will be apparent to those skilled in the art.

While there is in this application specifically described one form which the invention may assume in practice, it will be understood that this form of the same is shown for purposes of illustration, and that the invention may be modified and embodied in various other forms without departing from its spirit or the scope of the appended claims.

I claim:

1. In a balanced system of deep-well pumping, a pump head cylinder having a working stroke and a return stroke, a hydraulic fluid pump having discharge and intake connections, an accumulator, and means including a valve to connect the discharge connection with the pump head cylinder during the working stroke and

with the accumulator during the return stroke and to connect the intake connection with the accumulator during the working stroke and with the pump head cylinder during the return stroke, and including also a cutoff valve adapted, upon the occurrence of a condition relieving said cylinder of its working stroke load, to interrupt fluid flow to the pump head cylinder and to connect the pump discharge with the pump intake.

2. In a balanced pump head, in combination, a pump head cylinder, a piston reciprocable in the cylinder, a hydraulic fluid pump having a discharge connection and an intake connection, a control valve, an accumulator, means to conduct fluid under pressure from the pump to the valve, means to conduct fluid under pressure from the valve to the pump, said two conducting means including a cutoff valve adapted, upon the occurrence of a predetermined change in the pressure difference between pump discharge and pump intake, to interrupt fluid flow to the control valve and to connect the pump discharge with the pump intake, conduit means connecting the control valve with the cylinder, and conduit means connecting the control valve with the accumulator.

3. A balanced pumping head comprising, in combination, a pump head cylinder, a piston reciprocable in the cylinder, a hydraulic fluid pump having discharge and intake connections, a control valve, an accumulator, conduit means to conduct fluid under pressure from the fluid pump to the valve, conduit means to conduct fluid under pressure from the valve to said pump, a valve body having a central bore, connections communicating said bore with the first-named conduit means such that said conduit means includes at least a portion of the bore, connections communicating said bore with the second-named conduit means such that said conduit means includes at least a portion of the bore, a valve member reciprocable in the bore, the valve member having one operating position in which fluid flow is permitted from the pump to the control valve and from the control valve to the pump and another operating position connecting the pump discharge and intake connections and in which flow between the pump and the control valve is cut off, conduit means connecting the control valve with the cylinder, and conduit means connecting the control valve with the accumulator.

4. A combination according to claim 3, in which the valve member is biased toward one operating position by pressure in the conduit means from the pump to the control valve and toward its other operating position by pressure in the conduit means from the control valve to the pump, and means to prevent valve member movement from its first-named operating position to its second until the existence of a predetermined differential between the pressure in the conduit means from the pump to the control valve and the pressure in the conduit means from the control valve to the pump.

5. A combination according to claim 3, in which the valve member is biased toward its cutoff position by pressure in the conduit means from the pump to the control valve and toward its other operating position by pressure in the

conduit means from the control valve to the pump, and means to prevent valve member movement from its first-named operating position to its second until the pressure in the conduit means from the pump to the control valve is greater by a predetermined amount than the pressure in the conduit means from the control valve to the pump.

6. A combination according to claim 3, in which the valve member is biased toward one operating position by pressure in the conduit means from the pump to the control valve and toward its other operating position by pressure in the conduit means from the control valve to the pump, and spring-toggle-operated means to prevent valve member movement from its first-named operating position to its second until the pressure in the conduit means from the pump to the control valve is greater by a predetermined amount than the pressure in the conduit means from the control valve to the pump.

7. A balanced pumping head comprising, in combination, a hydraulic cylinder, a piston reciprocable in the cylinder, a hydraulic fluid pump, a control valve, an accumulator, means to conduct fluid under pressure from the pump to the valve, means to conduct fluid under pressure from the valve to the pump, the last two means including a cutoff valve mechanism adapted to interrupt fluid flow upon the occurrence of a predetermined change in load on the piston, conduit means connecting the control valve with the cylinder, conduit means connecting the control valve with the accumulator, and signal means connected to be actuated to give a signal upon movement of said cutoff valve to its cutoff position.

8. A combination according to claim 7, in which the signal means is electrically operated.

9. A combination according to claim 8, in which the signal means comprises an abutment mounted for movement upon movement of the cutoff valve into fluid-interrupting position, and a switch positioned to be engaged by said abutment and connected in the circuit of the signal means.

10. A combination according to claim 7, and means to drive said fluid pump; said signal means comprising means to stop the operation of said drive means.
